UNITED STATES PATENT OFFICE

105,200

DESIGN FOR A LEATHER FABRIC OR SIMILAR ARTICLE

Harry Cohen, New York, N. Y.

Application June 5, 1937, Serial No. 69,696

Term of patent 3½ years

To all whom it may concern:

Be it known that I, Harry Cohen, a citizen of the United States of America, residing in city of New York, county of New York, and State of New York, have invented a new, original, and ornamental Design for a Leather Fabric or Similar Article, of which the following is a specification, reference being had to the accompanying drawing, forming part thereof.

Fig. 1 is a plan view of a leather fabric or similar article, showing my new design.

Fig. 2 is a cross-sectional view taken on line 2—2 of Fig. 1.

The area included between the dot and dash lines constitutes the design unit, which unit is repeated in regular succession throughout the length of the leather fabric.

The animal elements on the leather fabric represent raised embossed areas.

I claim:

The ornamental design for a leather fabric or similar article substantially as shown and described.

HARRY COHEN.
